UNITED STATES PATENT OFFICE.

FRED E. WHITE, OF GARDNER, MASSACHUSETTS, ASSIGNEE TO CENTRAL OIL & GAS STOVE COMPANY, OF GARDNER, MASSACHUSETTS, A CORPORATION OF MASSACHUSETTS.

TANK FOR OIL-STOVES.

1,182,606.

Specification of Letters Patent.

Patented May 9, 1916.

Application filed November 12, 1914. Serial No. 871,761.

To all whom it may concern:

Be it known that I, FRED E. WHITE, a citizen of the United States, residing at Gardner, Massachusetts, have invented certain new and useful Improvements in Tanks for Oil-Stoves, of which the following is a specification.

This invention relates to liquid holding tanks and consists in providing a glass insert for the end of such a tank.

The invention is designed primarily for use on the cylindrical tanks forming the fuel reservoir on oil stoves, although its use is by no means limited to this.

The invention is illustrated in the accompanying drawings in which;

Figure 1 is a perspective view of a cylindrical tank with a glass insert in one end; Fig. 2 is a cross section through a diameter 20 of the tank end with its glass insert; Fig. 3 is a modification.

In the drawings the numeral 1 indicates the tank, 2 the end piece of the tank, and 3 the glass insert carried by the end piece.

4 indicates an inwardly turned flange on the end piece 2 forming a seat 5 for the glass 3, of such a depth that the glass is either flush with or below the outside of the end piece 2. The glass piece is formed with a cutaway portion 6, to permit the proper seating of the glass, and a circular ridge 7, adapted to engage the seat 5 of the flange 4. The glass recedes from the ridge 7 to form a tapering edge 8. To fill the space between this edge 8 and the flange 4, a strip of lead or other easily malleable metal 9 is forced until it bears upon the ridge 7 and firmly seats this ridge against the seat 5. The pressure exerted on the lead slightly bulges the flange 4, as shown at 10, which acts to more firmly hold the lead in place.

It will be observed that the periphery of the glass disk in front of the shoulder is slightly tapering toward the front and that the flange 4 tapers upwardly normally toward the front and hence the lead packing would normally, were it not for the bulge 10 be of practically V-shape and with noth-

ing to hold it in place against undue pressure as it would depend wholly upon frictional contact. By pressing in the lead however to make the bulge 10, it will be observed that a pocket is formed which allows for an accumulation of lead of greater thickness in the center line of the pocket than the mouth of the space through which the lead is inserted and hence the lead is positively prevented from being withdrawn and at the same time the connection made is absolutely an oil tight one.

I do not limit myself to the location of the glass 'disk' concentrically of the end of the tank for as shown in Fig. 3, it may be arranged eccentrically nearer the bottom and this will enable the bottom of the tank to be observed and the exact quantity in the tank seen. These tanks are usually filled from the bottom and another advantage is derived from the eccentric arrangement in that when the tank is inverted to be filled more accurate filling may be effected due to the nearness of the disk to the top of the tank when inverted.

I do not limit myself to the use of the disk of glass in the end of the tank though I prefer this and it may be located in the top or side of the tank.

What I claim is:

A fuel tank for oil stoves having end walls with an inturned flange the inner periphery of said flange being substantially concave, a glass disk fitting against a shoulder on the flange on one face, said disk having a peripheral projection and a space formed between the periphery of the glass and the concavity of the wall and a packing within said space adapted to lock the glass and flange together, said packing being within the parallel lines of the face of the glass, substantially as described.

In testimony whereof, I affix my signature in presence of two witnesses.

FRED E. WHITE.
